UNITED STATES PATENT OFFICE.

THOMAS W. KLOPP, OF PEORIA, ILLINOIS, ASSIGNOR TO THE CLEVELAND ARTIFICIAL LIMB CO., OF CLEVELAND, OHIO, A CORPORATION OF OHIO.

SUSPENSORY CONTROLLING DEVICE FOR ARTIFICIAL LIMBS.

No. 825,659.

Specification of Letters Patent.

Patented July 10, 1906.

Application filed October 2, 1905. Serial No. 280,860.

To all whom it may concern:

Be it known that I, THOMAS W. KLOPP, a citizen of the United States, residing at Peoria, in the county of Peoria and State of Illinois, have invented certain new and useful Improvements in Suspensory Controlling Devices for Artificial Limbs; and I do declare that the following is a full, clear, and exact description of the invention, which will enable others skilled in the art to which it appertains to make and use the same.

My invention consists in means adapted to suspend and control artificial limbs from the shoulders of the wearer, all substantially as shown and described, and particularly pointed out in the claims.

In the accompanying drawings, Figure 1 is a front view of my new and improved limb suspending and controlling outfit; and Fig. 2 is a rear view thereof, a dotted outline of a person being shown in each view. Fig. 3 is a side elevation, partly in section, of an artificial limb and a portion of the suspensory and actuating means. Fig. 4 is a cross-section of a portion of the knee-piece.

The artificial limb or leg members A and B are thus shown as pivotally connected at *a*, and upper member B is formed with a socket rounded at its bottom *b*, and in these particulars alone no novelty is claimed. Having an artificial limb like this or in substantially this form and style, with upper and lower members jointed together at a point corresponding to the natural knee-joint, as at *a*, it is desirable that the wearer should have as nearly a natural control of the limb as artificial means can provide. To this end I have devised equalizing means which are connected with both members A and B and have their supports and connections over both shoulders and at both front and rear of the person in such construction and relation that a shoulder action can be made effective for control of the limb with the least possible visible exertion and with the greatest possible ease. Thus I employ first a single endless cord or cable 2, which runs over small sheaves or other suitable bearings at every point where a turn of the cord is made and is without fixed attachment or connection throughout its length, as shown herein. This affords perfect freedom of action or play to said cord and has the further material ad-

vantage of enabling it to be shifted or moved along at points where greatest strain may come and which avoids wear or breakage.

C and D represent straps in a shoulder-support or harness for carrying and operating the leg. Said straps are of the usual suspender style, crossed and connected at *c* at the middle of the back, at which point also there is attached a suspender-strap 3, which hangs down the back and can be taken up or let out, as suspenders usually are. Each strap C and D passes over the shoulder and then around the side forward to the front of the person, where its end is attached to the front suspender portion of the other strap, thus constituting a harness-support through which the wearer finds it easy and natural to control the limb for locomotion through cord 2. Short adjustable suspender-straps 4 are employed in this instance as extensions of the front suspender ends of straps C and D, and each carries a sheave 5, over which cord 2 is engaged and adapted to run more or less as one or another movement of the limb is accomplished.

Now as further and auxiliary means essential to the successful operation of the foregoing parts I provide a sheave 6, which is located in the lower calf of the leg member A on a plane vertically behind pivot *a* and having cord 2 engaged over the same and run thence upward at a forward inclination in grooves or channels 6' in the knee portion *b* in front of pivot *a*, so as to effect such a leverage or purchase on the lower member with point 7 as a fulcrum as will enable said member to be promptly thrown to the front when a step is to be taken and even to hold it in such front and straightened position as long as desired, as in a natural leg. Obviously when tension on cord 2 is relaxed the said member is free to swing back, but within natural limits, also as in walking and as hereinafter more clearly seen. In all these movements the stump of the leg exercises its own rightful and helpful functions. An elastic strap *a'* is shown at the rear connecting the two members or sections A and B and adapted more especially to assist member A in its swing to the rear. From the point 7 at the front of the knee socket or joint the cord passes upward on slightly-diverging lines over sheaves 5 on the two suspenders 4, from

which the cord runs almost directly back and downward and onto sheaves 9 on the outer sides of upper leg member B, but with said sheaves 9 on slightly-different elevations in this instance. From these latter sheaves the strands or portions of the cord converge again and meet over sheave 10 on rear suspender-strap 3. Thus it is seen that as to the shoulder harness or support the cord 2 engages with each front suspender at a single point and with suspender 3 at the rear, making three distinct points of engagement and no more. Sheaves are employed here and there for cord 2 to run over and to avoid the friction and wear that would be unavoidably incurred if mere loops or other fixed bearings were used, and "cord" 2, so called, may be of any preferred material and size in cross-section. It will be noticed as peculiar to this construction that a single suspensory member at the middle of the back connects at the juncture of the two straps C and D, so that it will respond to action by either shoulder at a time, or by both, as may be, while at the front each strap C and D has a practically straight connection of its own down to the fulcrum and through which the cord actuates the lower limb. Of course cord 2 is always reasonably, but not uncomfortably or inconveniently, stretched, so that in fact the limb is made responsive to the movement of either shoulder alone if it be not convenient to exercise both for its actuation, and at the most the movement or movements of the shoulder are not necessarily considerable nor really noticeable when the body is in motion. By engaging cord 2 over sheave 6 at the rear of lower leg member A, I get the equivalent of a mechanical leverage and control of said member which is not exhausted when the leg is straightened, as in Fig. 3; but the effect is still more positive when the leg is bent backward, as is obvious. Of course I might attach the cord to the leg at this point instead of running over a sheave and largely preserve the equalizing effect of the entire harness; but this is not deemed best. A keeper 12 at the front and another keeper 13 at the rear confines the cord 2 at the upper end front and rear of leg member B. By reason of cord 2 being endless the pull or strain is equally distributed and there is play here and there in the working of cord 2 which makes it easy for the wearer. Keepers of a suitable kind might be substituted for the grooves or channels 6 in the knee-piece, or which is equivalent in position to the natural knee-cap, and whereby the cord is prevented from playing to one side of said joint. Lower leg member A is adapted to move from the action of the body and without shoulder action; but greater power and positive action

and control is given by my improved device as connected to the shoulders.

What I claim is—

1. In artificial limbs having upper and lower members, means to support and operate the lower member comprising a cord having a single point of engagement therewith and opposite engagements with the upper member, and a shoulder-support with which said cord is operatively connected at two points at the front and at a single point at the rear.

2. In artificial limbs, upper and lower limb members pivotally connected and harness to be worn over the shoulders, in combination with an endless controlling-cord having dual running engagement with the sides of said upper member and a single engagement with the lower member over the knee portion thereof, and having dual engagement with said harness at the front and a single engagement at the rear thereof.

3. Suspensory devices adapted to be used with artificial limbs consisting of a shoulder-harness having straps crossed in the back and the end of one strap crossed with the end of the other at the front and a single suspensory strap depending from the crossing of said straps at the rear, in combination with an endless limb-controlling cord having running engagement with said suspensory strap at the rear and separately with each of said crossed straps at the front.

4. In means for carrying and operating artificial limbs from the shoulders comprising a shoulder-harness having three suspensory portions, respectively, front and rear, in combination with upper and lower leg members and a single equalizing-cord having running engagement with said suspensory members and with the lower leg member at its rear below the knee-joint and engaged over the front of said joint, and an elastic strap connecting said leg members at the rear of said joint.

5. The combination of the shoulder-harness and the artificial-limb members, with a single cord engaged with the lower of said members below the knee-joint and in the rear portion thereof, and the said cord extending through said lower limb member at an inclination from the front and top thereof and a bearing for said cord at the front and lower portion of the upper of said limb members, thereby giving leverage to the cord to control the lower member.

In testimony whereof I sign this specification in the presence of two witnesses.

THOMAS W. KLOPP.
